DEFECATOR WITH INTEGRAL TANK AND
INTEGRAL EVACUATORWilliam C. Groeniger, Columbus, Ohio, assignor
to John B. Pierce Foundation, New York, N. Y.,
a corporation of New York

Application April 30, 1936, Serial No. 77,087

3 Claims.

(Cl. 4—13)

This invention relates to defecators i. e., water-closets, and more particularly to defecators comprising a bowl with rim channel flushing means, and a storage tank for a flushing liquid, usually 5 water, communicating with the rim-flow-channel of the bowl.

The present invention has as primary objects the elimination of whistling noises usually attending the flushing cycle of the above specified 10 types of defecators, the utilization of practically the entire liquid contents of the storage tank during each flushing cycle, and the provision for a positive after-fill of the well of the bowl, supplied, in a major degree, from the normal liquid 15 contents of the storage tank.

Such objects are accomplished by providing suitable air-venting means for the rim-flow-channel of the defecator bowl during the flushing cycle to prevent entrapment of air therein 20 and thus to eliminate syphonic action commonly operative on the supply stream from the storage tank to effect premature closure of the flush valve.

Pursuant to the present invention, embodiments thereof usually comprise a tank for the storage of flushing-liquid, a defecator bowl provided with a rim-flow-channel, a discharge conduit leading from the storage tank to the rim-flow-channel and operative to originate and 30 maintain a unidirectional flow of flushing liquid around the rim-flow-channel, an over-flow channel within the storage tank, and means affording communication between the over-flow-channel and the rim-flow-channel at a location adjacent 35 the termination of the flow-stream in the rim-flow-channel.

Advantageously, embodiments of this invention include a defecator of the type disclosed in my co-pending application for U. S. patent Serial No. 40 25,475, filed June 7, 1935, wherein a defecator bowl of the type disclosed in my copending application Serial No. 749,069, filed October 19, 1934 is novelly combined with an evacuator of the general nature of that disclosed in my copending application Serial No. 4,620, filed February 2, 1935. Preferred embodiments incorporate the storage tank integrally with the defecator bowl, and, desirably, also integrally with the evacuator.

50 A preferred embodiment of the present invention showing a defecator bowl integrally combined with an evacuator according to the above referred to copending applications, and a storage tank integrally incorporated therewith, is illustrated in the accompanying drawings, in which:

Fig. 1 represents a vertical central section through such embodiment.

Fig. 2 is a top plan view, hidden channels being indicated by dotted lines.

Fig. 3 represents a vertical section taken on the line 3—3, Fig. 1.

Fig. 4 represents a horizontal section taken on the line 4—4, Fig. 1.

Referring to the drawings and to the therein illustrated embodiment of this invention, the 10 unitary combination of a defecator bowl 10, a storage tank 11, and an evacuator 12 is of the wall-hung type and is suitably secured with its substantially planar, vertical back face 13 against a wall, or equivalent, indicated at 14. Such defecator combination discharges laterally through the opening 15 into component piping (not shown) of a waste disposal system.

In the particular embodiment, the rim-flow-channel 16 comprehends the upper periphery of 20 the bowl 10 and has branching therefrom at its front a downflow channel 17 terminating in a main flush-jet orifice 18 anteriorly of the well 19 of the bowl. Also, branching from the rim-flow-channel 16 at an appropriate location is a 25 downflow conduit 20 terminating in the vortex-effecting-jet orifice 21, located advantageously in an interior wall of the bowl near the maintained surface level 22a of the liquid after-fill 22. The rim-flow-channel 16 is provided with a plurality 30 of jet openings 23 spaced along its underside periphery.

The up-flow leg 24 of the evacuator 12, at its lower end communicates with the well 19 of the bowl 10 at a location opposite posteriorly the 35 main flush-jet orifice 18, and at its upper end opens into the down-flow leg 25. Such down-flow-leg communicates with the lateral discharge opening 15.

The lower portion of the upper wall of the up-flow leg 24 advantageously forms the rear wall of the bowl, and the upper wall of the down-flow leg 25 advantageously forms the lower wall of the up-flow leg 24.

The tank 11 for the storage of flush liquid rises integrally from the upper portion of the evacuator 12 posteriorly of the defecator bowl 10 and includes preferably integrally therewith the over-flow-channel 26. The bottom wall of the tank 11 advantageously forms the top wall of the 50 evacuator 12.

The present invention is concerned primarily with the cooperative relationship of the storage tank, and its therewith included overflow chan-

45

50

55

nel, to the rim-flow-channel of the defecator bowl.

In a defecator embodying a rim-flow-channel, for purposes of efficiency during the flushing cycle, i. e., the elimination of whistling noise, quickness and positiveness of flushing action, and utilization of substantially the entire contents of the storage tank, it is desirable to displace all of the air in the rim flow channel with water 10 at the beginning of the flushing cycle, and to displace the water in such rim-flow-channel by air at the termination of the flushing cycle. To this end, embodiments of the present invention provide for unidirectional flow of flushing liquid 15 around the rim-flow-channel, and include air vent means proximate the termination of flow of such liquid. The air vent means is advantageously coincident with the over-flow channel in the storage tank.

20 In the particular embodiment of the drawings, a flow passage 30, see Fig. 3, affords connection between the storage tank 11 and the rim-flow-channel 16. Such flow passage 30 is advantageously positioned adjacent a lateral side of 25 the storage tank for originating and maintaining unidirectional flow around the rim-flow-channel 16. The over-flow-channel 26 is preferably positioned proximate the front wall of the storage tank 11 and communicates at its lower end with, 30 and forms an upward extension of, the terminal end 16a of the rim-flow-channel 16. A wall 31 may separate the terminal end of the rim-flow-channel from the intake or supply end. The down-flow conduit 20, terminating in the vortex-effecting-jet orifice 21, preferably branches from the rim-flow-channel 16 at a location adjacent the inflow passage 30.

During the flushing cycle of the defecator, the over-flow channel 26 of the storage tank 11 40 constitutes an adequate air vent for the rim-flow channel. When the flushing cycle is initiated by opening a suitable valve (not shown), normally closing the inflow passage 30 between the storage tank 11 and the rim-flow-channel 16, the liquid content of the tank 11 flows unidirectionally into and around the rim-flow-channel 16, as appears clearly from Fig. 4, supplies the down-flow conduit 20, the down-flow channel 11, and the plurality of jet openings 23 with flushing liquid, 45 and seeks its level in the over flow channel 26. Thus, entrapment of air within the rim-flow-channel is precluded, as is also retardation of flow of liquid through such channel and through the branch channels. The overflow channel 26 50 constantly affords an air vent therefor. That liquid tending to remain in the lower portion of the overflow channel 26 at the termination of

the flushing cycle, flows backwardly around the rim-flow-channel to supply the after-fill to the well of the bowl.

Whereas, I have described my invention by reference to specific forms thereof, it will be understood that many changes and modifications may be made without departing from the spirit of the invention as set forth in the following claims.

I claim:

1. In a defecator having a storage tank for flushing liquid and a bowl with a rim-flow-channel, a discharge conduit from said storage tank to said rim-flow-channel arranged to originate and maintain unidirectional flow of flushing liquid around said rim-flow-channel, an over-flow channel within said storage tank, means for causing termination of the flow stream in said rim-flow-channel and passage means affording communication between said over-flow channel 20 and said rim channel at a location adjacent the termination of the flow-stream in the rim-flow-channel.

2. In a defecator having a storage tank for flushing liquid and a bowl with a rim-flow-channel, a discharge conduit from said storage tank to said rim-flow-channel, an over-flow channel within said storage tank communicating at its lower end with the rim-flow-channel adjacent the said discharge conduit, and a wall disposed in said rim-flow-channel between the said discharge conduit and the opening of said over-flow channel.

3. As an integral structural entity, a defecator having a bowl provided with a rim-flow-channel; an evacuator disposed at the rear of the bowl and having an up-flow leg and a down-flow leg, the up-flow leg having the lower portion of its upper wall in common with the rear wall of the bowl; a water storage tank disposed above the level of the bowl proximate the evacuator and having its bottom wall in common with the top wall of the evacuator; and an overflow channel disposed in the said storage tank throughout substantially the height thereof and opening at 45 its upper end into the storage tank and at its lower end into the rim-flow-channel; ports, inclusive of a main-jet channel, opening from the rim-flow-channel into the interior of the bowl; a valve-controlled passage between the said storage tank and the rim-flow-channel for initiating unidirectional flow of flushing liquid around the rim-flow-channel; and a wall in the rim-flow-channel separating the opening of the said passage from the opening of the overflow channel. 50

WILLIAM C. GROENIGER.
